FIG. 2 is a first perspective view of a first part of the multifunctional pet grooming device in FIG. 1;

FIG. 3 is a second perspective view of the first part of the multifunctional pet grooming device in FIG. 1;

FIG. 4 is a front view of FIG. 2;

FIG. 5 is a rear view of FIG. 2;

FIG. 6 is a left side view of FIG. 2;

FIG. 7 is a right side view of FIG. 2;

FIG. 8 is a top view of FIG. 2;

FIG. 9 is a bottom view of FIG. 2;

FIG. 10 is a first perspective view of a second part of the multifunctional pet grooming device in FIG. 1;

FIG. 11 is a second perspective view of the second part of the multifunctional pet grooming device in FIG. 1;

FIG. 12 is a front view of FIG. 10;

FIG. 13 is a rear view of FIG. 10;

FIG. 14 is a left side view of FIG. 10;

FIG. 15 is a right side view of FIG. 10;

FIG. 16 is a top view of FIG. 10;

FIG. 17 is a bottom view of FIG. 10.

FIG. 18 is a first perspective view of a third part of the multifunctional pet grooming device in FIG. 1;

FIG. 19 is a second perspective view of the third part of the multifunctional pet grooming device in FIG. 1;

FIG. 20 is a front view of FIG. 18;

FIG. 21 is a rear view of FIG. 18;

FIG. 22 is a left side view of FIG. 18;

FIG. 23 is a right side view of FIG. 18;

FIG. 24 is a top view of FIG. 18;

FIG. 25 is a bottom view of FIG. 18;

FIG. 26 is an assembled perspective view of the first and second parts of the multifunctional pet grooming device;

FIG. 27 is an assembled perspective view of the multifunctional pet grooming device in FIG. 1; and,

FIG. 28 is an enlarged view shown in FIG. 10.
